Re. 16,731

UNITED STATES PATENT OFFICE.

WILLIAM MAYER, OF NEW YORK, N. Y.

TRAILER COUPLER.

Original No. 1,550,555, dated August 18, 1925, Serial No. 689,454, filed January 30, 1924. Application for reissue filed December 4, 1926. Serial No. 152,706.

This invention relates to tractors and trailers and particularly to an improved coupling mechanism therefor including power mechanism for causing an actuation 5 of certain of the connecting parts.

Heretofore in the prior practice of effecting the coupling of tractors and the like to trailers, various devices and mechanisms have been designed for the purpose, and 10 have to a greater or lesser extent been successful to meet the requirements of the types and classes of those vehicles in use at the time of their development. However, in the 15 elapsed time since the prior types of such devices and mechanisms were brought into existence, the types and classes of tractors and trailers have changed, so as to render the successful use of the devices or mechanisms aforesaid practically obsolete and of 20 little value to meet the heavy duty requirements called for in the handling of loads ranging up to forty (40) tons or more as is now of common occurrence, or, at least, not without serious modification and refinement 25 in arrangement and construction. The present invention is designed to meet these modern demands and requirements, and provides for the raising and lowering of the ends of the trailer to be coupled both before and 30 after the coupling operation, and regardless of the weight of the load carried, at the time, by the trailer. Not only does the present structure provide for the raising and lowering of these heavy loads, but it also provides for a range of lift to amply compensate 35 for vehicle supporting spring compression under such heavy loads and in a manner that the coupling operation may be readily and easily accomplished without in any way 40 disturbing or otherwise necessitating a displacement or shifting of a load to that desired end.

The principal object of the present invention is, therefore, to provide for a device 45 or mechanism of the character mentioned, and one embodying certain mechanical refinements in construction and arrangement of parts and cooperative devices or mechanisms, which will be capable of effectively 50 and efficiently meeting any and all conditions involved in the coupling together of the heavy duty types of tractors and trailers, and to overcome certain serious disadvantages. difficulties and mechanical defects res-

ident in the known types of such devices or mechanisms.

An object of the invention is to provide an improved construction wherein means are provided for connecting the engine of the tractor to certain parts of the coupling 60 mechanism for raising the trailer at one end when it is desired to uncouple the same.

Another object is to provide a coupling for tractors and trailers wherein the moving parts may be actuated from the engine 65 of the tractor without stopping the engine.

An additional object is to provide a coupling structure for trailers in which the trailer is raised from power derived from the tractor engine, the same being associated 70 with an adjustable support for the trailer capable of supporting the same after it has been arranged and the tractor removed.

A further object is to provide an improved structure which will effect a coupling 75 between power tractors or trucks, with trailers designed for exceedingly heavy loads, the structure being such also as to permit the raising and lowering of one end of the trailer and its load during the coupling and 80 uncoupling action.

In the accompanying drawings—

Figure 1 is a side view of part of a tractor and trailer, with couplings embodying the invention shown applied thereto. 85

Figure 2 is a view similar to Figure 1 but showing the trailer elevated with the elevating means moved back to their former position.

Figure 3 is an enlarged fragmentary view 90 of the lower part of the support shown in Figures 1 and 2, illustrating how the pawls thereof may be thrown out of engagement.

Figure 4 is a top plan view of the rear 95 part of the tractor showing part of the coupling mechanism and the king pin of the trailer in section.

Figure 5 is a transverse vertical sectional view through Figure 4, approximately on line 5—5 of Figure 4. 100

Figure 6 is a longitudinal vertical sectional view through Figure 4, approximately on line 6—6 in Figure 4.

Figure 7 is a fragmentary longitudinal 105 sectional view through Figure 4, approximately on line 7—7 in Figure 4.

Referring to the accompanying drawings by numerals, 1 indicates a tractor of any

desired kind and 2 a trailer adapted to be connected to the tractor 1 and disconnected therefrom whenever desired. The particular construction of the tractor 1 and the trailer 2 forms no part of the present invention but only the coupling and associated structures. The invention also includes a coupling structure which functions to take care of exceedingly heavy loads. During the coupling and uncoupling, the structure acts to raise and lower effectively, not only the coupling mechanism, but one end of the trailer with the load.

As indicated in Figure 1, a standard 3 is provided pivotally mounted at 4 to the trailer 2 and acting to support the trailer as indicated in Figure 2 when the tractor 1 is moved away. The standard 3 is provided with a bar 5 swingingly supported at 4 and provided with oppositely extending ratchet teeth 6 for receiving the respective pawls 7 and 8. These pawls are carried by a base 9 into which the lower end of the rod 5 extends. The pawls 7 and 8 have suitable pivotal supports which extend to the exterior of the base 9 and connected to these pivotal supports are arms 10 and 11 connected by a link 12 (Figure 3,) whereby upon the actuation of the crank member 13 secured to arm 10, both pawls may be thrown into and out of operation at any time.

When the trailer is being pulled by the tractor 1, the standard 3 is arranged as shown in dotted lines in Figure 1 and supported by a suitable hook 14 or other suitable supporting members. When it is desired to lift the trailer at a given point and move the tractor away, the standard 3 is swung down to the full line position shown in Figure 1 and then the parts actuated as hereinafter fully described for elevating the trailer 2 as shown in Figure 2 whereupon the tractor 1 may be readily moved away.

In order to raise the front of the trailer 2 as shown in Figure 2 and to lower the same, special mechanism is provided on the tractor 1 which is adapted to be actuated in both directions by the engine of the tractor. In Figure 4, will be seen a top plan view of the rear part of the tractor from which it will be seen that a bolster 15 is provided which extends from near one side to near the opposite side of the tractor and which is flat but rounded at each end and enlarged or swelled outwardly horizontally in the center. A suitable aperture 16 is provided in the center of the bolster 15 as shown in Figure 5, said aperture being adapted to receive the coupling pin or king pin 17, preferably formed integral with the plate 18, which plate is bolted or otherwise rigidly secured to the bottom of the trailer 2. When the pin 17 is in the position shown in Figure 5, the trailer and tractor are coupled together. From Figure 7, it will be

noted that the pin 17 is provided with a groove 19 for receiving a locking yoke 20, which yoke may be formed integral with the arm 21 or may be mounted in some other manner whereby it can be moved into and out of engagement with the pin 17. A hand lever 22 is rigidly secured to or formed integral with the arm 21 and a suitable pivotal pin 23 extends through the juncture of the arm 21 and lever 22, said pin extending into the bolster 15. A plate 24 is bolted or otherwise rigidly secured to the bolster 15 and extends at right angles thereto for a short distance as shown in Figure 4, in order to receive the removable pin 25.

When the parts are in the position shown in Figure 4, the yoke 20 is positioned in the groove 19 and, consequently, the coupling pin 17 is locked against disengagement. When it is desired to disengage the coupling pin, the pin 25 is removed and the lever 22 may be moved over to the dotted position shown in Figure 4 and pin 25 re-inserted whereupon yoke 20 will be locked in an outer position.

As both sides of the device are identical, the description of one will apply to both. As indicated particularly in Figures 5 and 6, the ends of the bolster 15 are provided with rounded sections 26 which rest in a suitable head 27 merging into a threaded vertical screw 28. A binding or retaining strap 29 of sheet metal is mounted over the rounded portion 26 and is secured to the head 27 by a suitable pin 30. The head 27 with its strap 29, is mounted to reciprocate in a vertical guide 31 which is U-shaped in cross section, with the open part of the structure facing inwardly. In other words, a deep channel iron is used for forming the guide 31, said channel iron being secured by welding or otherwise to the socket member 32 which in turn is mounted on the transverse U-shaped channel 33 forming part of the tractor frame. The socket member 32 may be secured in place in any desired manner but ordinarily it may be retained in place by friction and said socket member having outwardly turned flanges 34 and 35 at the top so as to distribute the strain over all parts of the channel iron 33 at the end thereof. The screw 28 extends through the socket member 32 and also the channel iron 33 as indicated in Figures 5 and 6 and through the worm gear 36, which gear is provided preferably with an elongated shank 37, internally threaded for receiving the screw 28. The shank 37 is preferably provided with a flange 38 so as to receive suitable anti-friction bearings 39, said bearings being mounted in any desired manner on the channel iron 33. The worm gear 36 continually meshes with the worm 40 secured to the shaft 41 whereby whenever the shaft 41 is rotated, the worm gear will be rotated.

and, consequently, the screw 28 will be raised or lowered according to the direction of rotation of the various parts. As the duplicate of this same structure is on the opposite side and operated by the same shaft 41, the bolster 15 will be raised and lowered as the case may be.

In order to secure a proper drive for the shaft 41 and associated parts, the said shaft 10 is provided with a sprocket wheel 42 for accommodating the chain 43, which chain passes over a sprocket wheel 44 rigidly secured to the shaft 45. The shaft 45 is mounted in suitable bearings connected with 15 the various parts of the tractor and has a bevel gear 46 rigidly secured thereto near one end. This bevel gear co-acts with the bevel pinions 47 and 48, which pinions are moved into mesh with the bevel gear whenever 20 it is desired to raise or lower the bolster 15. The pinions 47 and 48 are rigidly secured to a shaft 49 supported by suitable bearings which will permit the shaft to freely rotate and also freely reciprocate. This 25 shaft near the front is provided with a pair of gear wheels 50 and 51, said gear wheels being spaced a short distance apart and capable at different times of meshing with the driving pinion 52 secured to the shaft 30 53 extending from the transmission 54 or connected to the propeller shaft of the engine where there is no power take-off shaft in the transmission. The transmission 54 is of any usual or preferred type used on tractors and, therefore, will not need a detail description.

The shaft 49 is reciprocated by any suitable means, as for instance, a hand lever 55, said lever extending either to the driver's 40 seat or to some other convenient point. When the tractor is operating to pull the trailer, the gear wheels 50 and 51 are in the position shown in Figure 6. If it should be desired to remove the trailer from the tractor, the shaft 49 is shifted until the gear 45 wheel 51 fully meshes with the pinion 52. When this occurs, the bevel pinion 47 will be in mesh with the bevel gear 46. The tractor engine is preferably operating before or 50 at the time this takes place but the clutch is released which naturally stops the gear 52 to permit the ready engagement of the gear 55 wheel 51. After the gear wheel 51 has been properly brought into mesh, the clutch is again thrown in so that the shaft 45 will immediately begin to rotate which will transmit power to the shaft 41 and from thence to the worm 40 and worm gear 36 co-acting with the respective screws 28 for raising 60 the bolster 15 and associated parts.

Before this raising action has taken place, it will be necessary to shift the lever 22 to the dotted position shown in Figure 4 in order to release the pin 17. When this has 65 been done and the bolster 15 has been raised

to substantially the position shown in Figure 2, the shaft 49 and associated parts are moved back to the position shown in Figure 6 but the engine of the tractor is not stopped. When this has been done, the operator assures himself that the standard 3 has properly functioned and drives the tractor away to the desired point. Preferably, before the tractor is driven away, the bolster 15 and associated parts are lowered to their former 70 position. To do this, the clutch is again released and the shaft 49 moved in a reverse direction a sufficient distance to cause the gear wheel 50 (Figure 6) to mesh with pinion 52 and the bevel pinion 48 to mesh with the bevel gear 46. After this shifting of gears has taken place, the clutch is again operated and the parts will be actuated whereupon the worm wheel 36 and associated parts will be actuated for moving the bolster 15 downwardly to its former position, namely, the position shown in Figure 5. The clutch is again released and shaft 26 moved until the parts are moved to a neutral position as shown in Figure 6. The clutch may be again let in and the tractor started in the usual way.

When it is again desired to connect the tractor to the trailer, the tractor is backed into position, as for instance, into the position shown in Figure 2 and lever 55 is again shifted for causing the gear 51 to mesh with the pinion 52. When backing the tractor in position, it may be backed directly in line as shown in Figure 1, or backed into position from different angles, as for instance, a ninety degree angle. This is very desirable, as quite often the width of the street or other objections, prevents the tractor from backing in from a front position. After the tractor has been backed into position, lever 55 is shifted as above set forth for causing the gear 51 to mesh with the pinion 52. This will cause the bolster 15 to become elevated and the elevation is continued until the pin 17 is in the position shown in Figure 5 and in fact, until the forward end of the trailer 2 has been lifted slightly. When this has occurred, the parts are moved to the neutral position shown in Figure 6 and the standard 100 3 is manually shifted to the position shown in dotted lines in Figure 1. The shaft 49 is again operated to move the gear wheel 50 into mesh with the pinion 52 in order to cause the parts to be actuated for again lowering the bolster 15 to substantially the position shown in Figure 5. When it has reached this position, the parts are again moved to the neutral position shown in Figure 6 and the trailer and tractor are coupled, ready for use together.

In coupling and uncoupling, the parts will function for accomplishing this result without the use of the locking lever, though ordinarily, some form of lock is desirable.

Where the trailer is carrying a heavy load, the lock might be dispensed with but where it is carrying a light load the lock is preferable. Also, it will be evident that the raising and lowering means of the bolster may be used with the particular pin described or some other form of coupling that will accomplish the desired results, as for instance, the usual coupling now in common use.

10. What I claim is:

1. A coupling for heavy duty trailers and tractors, comprising a coupling member adapted to be connected with the trailer, a bolster adapted to be mounted on the tractor, said bolster having means for interlocking with said coupling member, a pair of reciprocating members for raising and lowering said bolster and the end of said trailer with or without load, said reciprocating members being threaded at their lower ends, means for guiding said reciprocating members and said bolster in their movement, a worm gear provided with a threaded bore for receiving each of said threaded members, a worm meshing with each of said worm gears, a shaft connecting said worms whereby they will be operated simultaneously, and means connecting said shaft with the engine of the tractor for actuating said shaft 25 and gear wheels to actuate said reciprocating members, said means including a reversing mechanism whereby said shaft may be rotated in either direction by power from the engine.

2. In a coupling for heavy duty tractors and trailers, a coupling member connected with the trailer, a bolster formed with means for interlocking with said coupling member, said bolster being mounted on said tractor, means for moving said bolster into and out of engagement with said coupling member and also raising and lowering one end of the trailer with or without load, said means including a plurality of threaded rods arranged vertically, a gear wheel threaded onto each of the threaded rods, a co-acting gear for each of the gear wheels for actuating the same, said first mentioned gear wheels being fixed whereby as they are rotated the threaded members and bolster will be raised and lowered according to the direction of rotation, a shaft for rotating said co-acting gears, and a plurality of means for connecting said shaft with the engine of the tractor, said plurality of means including a power gear connected with the engine and rotated thereby, a forwardly driving gear, a train of reversing gears, a hand operated member for shifting said forwardly driving gear and said train of reversing gears respectively into and out of mesh with said power gear for causing a connection and disconnection with said engine and a reversal of said gears according to the direction of movement of said hand operated member.

3. In a coupling for heavy duty trailers and tractors, a coupling member carried by the trailer, a vertically movable bolster for interlocking with said coupling member, said bolster being mounted on a tractor, means for connecting the engine of the tractor with the bolster for causing the bolster to be moved upwardly and downwardly, said means including a reciprocating shaft, manually actuated means for reciprocating said shaft, a pinion connected with said engine, a pair of gear wheels mounted rigidly on said shaft and spaced apart a proper distance so that when said shaft is moved in one direction to its extreme position, one of the gear wheels will mesh with said pinion and when moved to its opposite extreme position, the other of the gear wheels will be in mesh with said pinion, a pair of bevel pinions mounted on said shaft and spaced apart, a bevel gear adapted to mesh at different times with said pinions, said bevel pinions being spaced apart a proper distance to be moved into engagement with said bevel gear when said shaft is moved to its respective extreme positions, a pair of threaded members connected with said bolster, a fixed worm gear threaded onto said threaded members and means for driving said worm gears from said bevel gear.

4. A heavy duty trailer hoist and coupler comprising a coupling member connected with the trailer, a bolster adapted to be mounted on a tractor and formed with means for interlocking with said coupling member, means on the tractor for raising and lowering said bolster into and out of engagement with said coupling member, said means including a forward and a reversing drive mechanism operatively connected with the engine of the tractor whereby the engine of the tractor will raise and lower the bolster, and the end of the trailer with or without load, manually shiftable means for shifting said drive mechanism for connecting the engine with the raising and lowering means, and means associated with the bolster for locking said coupling member in engagement with the bolster when the parts are in coupling position.

5. In a coupling for trailers and tractors, a coupling member carried by the trailer, a vertically movable bolster for receiving said coupling member, said bolster being mounted on a tractor, means for connecting the engine of the tractor with the bolster for causing the bolster to be moved upwardly and downwardly, said means including a reciprocating shaft, manually actuated means for reciprocating said shaft, a pinion connected with said engine, a pair of gear wheels mounted rigidly on said shaft and spaced apart a proper distance so that when said shaft is moved in one direction to its extreme position, one of the gear

wheels will mesh with said pinion and when moved to its opposite extreme position, the other of the gear wheels will be in mesh with said pinion, a pair of bevel pinions 5 mounted on said shaft and spaced apart, a bevel gear adapted to mesh at different times with said pinions, said bevel pinions being spaced apart a proper distance to be moved into engagement with said bevel gear 10 when said shaft is moved to its respective extreme positions, and means for driving said worm gears from said bevel gear.

6. A coupling and hoist for a tractor and heavy duty trailer comprising interlocking 15 coupling members, one of said members acting as a hoisting member, a plurality of vertically movable reciprocating members for raising and lowering said hoisting member and simultaneously raising and lowering 20 one end of the trailer with or without load, means for guiding said reciprocating members and said hoisting member in their movement, a gear for each of the reciprocating members for raising and lowering 25 the same, means connecting said gears with the engine of the tractor for causing an actuation thereof, said last mentioned means including a forward driving gear, a train of reversing gears, a power gear connected 30 with the engine and adapted to be rotated in one direction, and shiftable means for causing said forward driving gear and said train of reversing gears to be connected and disconnected with said power gear.

35 7. A heavy duty trailer coupling, comprising a coupling member adapted to be connected with a trailer, a bolster adapted to be mounted on a tractor and formed with means for receiving said coupling member, 40 means on the tractor for raising and lowering one end of said trailer, with or without load, while raising and lowering said bolster into and out of engagement with said coupling member, said means being operatively connected with the engine of the tractor 45 whereby the engine of the tractor will raise and lower the bolster, manually shiftable means for connecting and disconnecting the engine from the raising and lowering 50 means, said manually shiftable means including a reversing mechanism, and manually shiftable means carried by the bolster for locking said coupling member in engagement with the bolster when the parts 55 are in coupling position.

8. A coupling and hoist for a heavy duty tractor and trailer comprising interlocking coupling members, one of said members acting as a hoisting member, means on the 60 tractor for raising and lowering said hoisting member into and out of engagement with the other coupling member, said means being operatively connected with said raising and lowering means and with the engine 65 of the tractor whereby the engine of the

tractor will raise and lower the hoisting member, and shiftable means including a reversing mechanism for connecting and disconnecting the engine with the raising and lowering means, said shiftable means including a manually actuated member. 70

9. A coupling and hoist for a heavy duty tractor and trailer comprising interlocking coupling members, one of which acts as a hoisting member, a plurality of vertically 75 movable members mounted on the tractor for raising the hoisting member and one end of the trailer, with or without load, while causing said coupling members to interlock, means including toothed members 80 for raising and lowering said vertically movable members, connecting means for operatively connecting the last mentioned means with the engine of the tractor whereby the engine of the tractor will furnish 85 power for raising and lowering the hoisting member, and means including a reversing mechanism for connecting and disconnecting the engine with said connecting means. 90

10. A coupling and hoist for a heavy duty tractor and trailer comprising a coupling member, a bolster having means for receiving said coupling member, a vertically 95 movable structure on the tractor for causing the coupling member and bolster to be engaged and disengaged, said vertically movable structure acting to raise the end of said trailer, with or without load, when moved to a coupling position, means operatively 100 connected with said vertically movable structure and with the engine of the tractor whereby the engine of the tractor will cause said vertically movable structure to function, and shiftable means including a reversing mechanism for connecting and disconnecting the engine with said raising and lowering means, said shiftable means including a manually actuated member for moving the shiftable means in one direction. 105

11. A hoist and coupler for a heavy duty tractor and trailer comprising a coupling member adapted to be connected with the trailer, a bolster adapted to be mounted on a tractor and formed with an opening for receiving said coupling member, means on the tractor for raising and lowering said bolster into and out of engagement with said coupling member, said means acting to lift 115 one end of the trailer, with or without load, when the bolster is raised, said means being operatively connected with the engine of the tractor whereby the engine of the tractor will raise and lower the bolster, 120 manually shiftable means including a reversing mechanism for connecting the engine with the raising and lowering means, and means associated with the bolster for locking said coupling member in engagement 125 130

with the bolster when the parts are in coupling position.

12. A hoist and coupler for a heavy duty tractor and trailer comprising a coupling member adapted to be connected with a trailer, a bolster adapted to be mounted on a tractor and formed with means for receiving said coupling member, means on the tractor for raising and lowering said bolster into and out of engagement with said coupling member, said means being operatively connected with the engine of the tractor whereby the engine of the tractor will raise and lower the bolster, and also the end of the trailer with or without load, shiftable means for connecting and disconnecting the engine with the raising and lowering means, said shiftable means including a reversing mechanism and manually actuated member for causing the engine to be connected with said raising and lowering means, and shiftable means for locking said coupling member in engagement with the bolster when the parts are in coupling position.

13. A coupling and hoist for a heavy duty tractor and trailer comprising interlocking coupling and hoisting members, vertically movable members on the tractor for raising and lowering said hoisting member, and the end of said trailer with or without load, means including a reversing mechanism for operatively connecting said raising and lowering means with the engine of the tractor whereby the engine of the tractor will raise and lower the hoisting member, and shiftable means for connecting and disconnecting the engine with the raising and lowering means, said shiftable means including a manually actuated member.

14. A heavy duty tractor and trailer hoist and coupler comprising interlocking coupling members, one of said members also acting as a hoisting member for raising the end of the trailer with or without load and

the coupling members into coupling position, a vertically movable structure on the tractor for causing the coupling member to engage and disengage, means including a reversing mechanism operatively connected with said vertically movable structure and with the engine of the tractor whereby the engine of the tractor will cause said vertically movable structure to function, and shiftable means for connecting and disconnecting the engine with the raising and lowering means, said shiftable means including a manually actuated member for moving the shiftable means in one direction.

15. A trailer hoist and coupler comprising a coupling member and a hoisting member, said members being adapted to interlock, a movable structure on the tractor for raising and lowering said hoisting member and the end of the trailer, means for operatively connecting said movable structure with the engine of the tractor whereby the engine of the tractor will raise and lower said hoisting member, and means for locking said hoisting member and said coupling member together.

16. A heavy duty trailer hoist and coupler comprising interlocking coupling and hoisting members, movable means on the tractor for raising and lowering said hoisting member, said movable means also functioning to raise and lower one end of the trailer with or without load, means for operatively connecting said movable means with the engine of the tractor whereby the engine of the tractor will raise and lower said hoisting member, means for locking together said interlocking coupling and hoisting members, and shiftable means for connecting and disconnecting the engine with the raising and lowering means, said shiftable means including a manually actuated member.

WILLIAM MAYER.
